UNITED STATES PATENT OFFICE

137,768

DESIGN FOR A FISH DISPLAY DEVICE OR SIMILAR ARTICLE

Eugene C. Lehman and Lloyd W. Shirley, Minneapolis, Minn., assignors to Brown & Bigelow, St. Paul, Minn., a corporation of Minnesota

Application February 9, 1942, Serial No. 105,720

Term of patent 14 years

(Cl. D31—4)

To all whom it may concern:

Be it known that we, Eugene C. Lehman and Lloyd W. Shirley, citizens of the United States, residing at Minneapolis, county of Hennepin, and State of Minnesota, have invented a new, original and ornamental Design for a Fish Display Device or Similar Article, of which the following is a specification, reference being had to the accompanying drawing, forming part thereof.

Fig. 1 is a perspective view of a fish display device or similar article, showing our new design;

Fig. 2 is a top plan view thereof;

Fig. 3 is a side view;

Fig. 4 is a view showing the opposite side;
Fig. 5 is a bottom view; and

Fig. 6 is a front view of the fish design.

In Figure 6 we have illustrated a front view of our fish display device showing the manner in which the top and bottom are colored or decorated with a solid color, whereas one of the sides has a longitudinal line extending thereto from the front to the back as illustrated in Figures 1 and 6.

We claim:

The ornamental design for a fish display device or similar article, as shown.

EUGENE C. LEHMAN.
